PROTECTIVE COVER FOR STRAW HATS

Robert B. Hock, Goshen, N. Y.

Application June 28, 1932. Serial No. 619,623

5 Claims. (Cl. 2—187)

This invention relates, generally, to improvements in protective covers for straw hats; and the invention relates, more particularly, to a novel foldable waterproof cover member associated in 5 a novel manner with the usual decorative ribbon band, with which such hats are provided, whereby, when not in use, said cover may be folded relative to the band so as to lie concealed behind the same.

10 This invention has for its principal object to provide, in combination with a detachable ribbon band for a straw hat, a novel foldable waterproof hat cover which folds into parallel underlying relation to said band so as to be concealed thereby when the band is normally applied around the crown of the hat, but which, when use thereof is desired in showery or rainy weather, may be unfolded and mounted upon the hat to form a covering member enclosing the crown 20 and brim thereof so as to protect the same from wetting.

This invention has for a further object to provide a novel form and relation of foldable parts designed to form a hat cover, together with means 25 to fasten such parts in operative cover forming relation ready to be applied upon and over the crown and brim of the hat.

Other objects of this invention, not at this time more particularly enumerated, will be understood 30 from the following detailed description of the same.

An illustrative embodiment of this invention is shown in the accompanying drawings, in 35 which:—

35 Fig. 1 is a side elevation of a straw hat having the detachable ribbon band and foldable waterproof cover member, with the latter folded so as to lie between the hat crown and said band, being thus readily available for use but being concealed 40 by the band until such use is desired; Fig. 2 is a top plan view of the same; Fig. 3 is a view of the hat band removed from the hat preparatory to unfolding of the cover member; Fig. 4 is an inside plan view of the removed hat band with the cover 45 member partially unfolded relative thereto preparatory to the operative disposal of the parts of the latter ready for use; and Fig. 5 is a side elevation of a hat with the cover member arranged in operative condition and applied over the crown 50 and brim of the hat as a protection thereto.

Similar characters of reference are employed in the above described views, to indicate corresponding parts.

55 Referring to said drawings, the reference character 6 indicates the crown of a straw hat and 7

the brim thereof. Arranged to encircle the hat crown 6 above the brim 7 is a ribbon band 8 such as is usually provided as a decorative element of the hat. This band 8 is of detachable form, comprising a discontinuous body having a suitably 60 formed bow formation 9 at one end, to the inner face of the free loop portion of which are secured female elements 10 of snap fastener devices. Secured to the opposite end of the band 8 are male elements 11 of said snap fastener devices. 65 Any other suitable form of fastener devices may be employed.

The novel foldable cover member which is associated with the band 8, comprises a substantially rectangular main body 12 formed from any 70 suitable waterproof or moisture resistant material, such as sheet rubber, rubberized fabric, oil-silk, or the like. This main body 12 is provided, intermediate its ends, with a plurality of perpendicularly extending pleats 13. The main 75 body 12 is overlaid upon the inner face of the band 8, and suitably secured thereto, as by stitching 14. In disposing said main body 12 in operative relation to said band 8, a free pleated marginal portion 15 of minor extent is formed 80 to extend beyond one longitudinal edge of the band, and a free pleated skirt portion 16 of major extent is formed to extend beyond the opposite longitudinal edge of the band. Connected with said marginal portion 15 intermediate its ends is a foldable top-sheet 17 having 85 a general outline shape approximating that of the top of the hat crown. Secured to the marginal portion 15, at suitable longitudinally spaced intervals, are male elements 18 of snap 90 fastener devices, and secured to the edge portions of the top-sheet 17 are suitably spaced female elements 19 of said snap fasteners. Adjacent to one end of said marginal portion 15 is an 95 eyelet or perforation 20, which at proper time, is engageable over the male snap fastener element 18 located adjacent the opposite end of said marginal portion 15. Owing to the portions of the pleats 13 which extend through said marginal portion 15, the latter is longitudinally expandable and contractible. In like manner, owing to the portions of the pleats 13 which extend through said skirt portion 16, the latter is likewise longitudinally expandable and contractible. 100 The folds of the portions of the pleats 13 which extend through said skirt portion 16 are provided with perforations 21, located adjacent to the free longitudinal edge of said skirt portion. Threaded through said perforations 21 is an 105 elastic strip or cord 22, the respective terminal 110

portions of which are suitably anchored or secured to the skirt portion, as by stitching or other suitable fastening means. Affixed to said skirt portion 16 at one end thereof, and adjacent to its free longitudinal edge, is a male element 23 of a snap fastener device, and in corresponding position at the other end thereof is fixed a female element 24 of said snap fastener device. It will be understood that any other suitable forms of cooperative fastener devices may be substituted for the described snap fastener elements with which the marginal portion 15, top sheet 17 and skirt portion 16 are shown to be provided.

When use of the cover member is not desired, the marginal portion 15 is folded over upon that portion of the main body 12 which is contiguous to the inner face of the band 8, and then the top-sheet 17 is folded upon itself to likewise overlie the folded marginal portion 15, as shown in Fig. 4. The skirt portion 16 is thereupon folded upon itself along the line $a-a$ in Fig. 4, and again folded along the line $b-b$ in Fig. 4, whereby it too is brought into overlying relation to the folded marginal portion 15 and top-sheet 17 and along the back of the band 8. When the cover member is thus folded upon itself, the band 8 is disposed around the hat crown 6, and its meeting ends secured together by the fastener devices 10-11, whereupon the completely folded cover member, as indicated by the reference character C in Figs. 2 and 3, will lie between the sides of the hat crown 6 and the band 8 so as to be concealed by the latter. In this manner the cover member is carried in connection with the hat so as to be always ready for instant use upon need therefor, and yet is so hidden from view as to avoid disturbing the normal and usual appearance of the hat as ordinarily worn. In the event of occurrence of showers or rain, the user may quickly obtain the cover member and by manipulation thereof unfold the same and rearrange its parts to form the operative protecting cover for application over the hat crown and brim. In preparing the cover member for such use, the following operations are performed:

First the band 8 is detached from the hat, reversed and then laid out lengthwise as shown in Fig. 4. The skirt portion 16 is then unfolded to extend downwardly therefrom, and the marginal portion 15 is unfolded to extend upwardly therefrom, while the top-sheet 17 is unfolded to spread condition (indicated by dotted lines in Fig. 4). The band 8 and body 12 is then applied around the sides of the hat crown 6, with the ends of the body 12 overlapped, and the ends of the band 8 secured again together by the fastener devices 10-11. The marginal portion 15 is thus disposed around the hat crown 6 above the band 8, whereupon its free edge portions may be inturned over the top of the hat crown, the pleat portions 13 therein permitting the necessary contraction of said edge portions to cause the same to conform to the contour of the crown. The eyelet or perforation 20 at one end of the marginal portion is engaged over the male fastener element 18 adjacent to the other end of said marginal portion, whereupon the top-sheet 17 is spread over the top of the crown, and over the inturned edge portions of said marginal portion 15, being then joined to the latter by engaging its female fastener elements 19 with the male fastener elements 18 of said marginal portion 15. The skirt portion 16 is extended out-

wardly from the lower edge of the band 8 over the hat brim 7, the pleated portions 13 permitting expansion thereof to spread the same over said hat brim, with the end portions of said skirt portion meeting in overlapping relation. The free edge portions of said skirt portion 16 are then inturned around and under the edge portions of the hat brim 7, and the end portions thereof joined together by engaging the fastener elements 23-24. In thus joining such end portions, the elastic strip or cord 22 is stretched, so that, when the fastener elements 23-24 are engaged, a drawing tension is exerted upon the free edge portions of said skirt portion 16 tending to contract or gather the same around and beneath the hat brim edge, thus securely attaching the cover member in operative relation to the hat, so as to be held thereto against accidental displacement.

From the above description, it will be apparent that a very novel and practical combined hat band and foldable cover member is provided for use with straw hats or the like; the same being so devised as to be wholly concealed by the hat band when not in use, but nevertheless capable of being quickly and easily unfolded and set up for application in protective covering relation to the hat in case of need, and so as to efficiently protect the hat against wetting when worn during showery or rainy weather.

As many changes could be made in the above construction and many apparently widely different embodiments of this invention could be made without departing from the scope thereof, as defined in the following claims; it is intended that all matter contained in the above description or shown in the accompanying drawings shall be interpreted as illustrative and not in a limiting sense.

I claim:

1. The combination with a detachable band for hats, of a hat cover member secured to the inner face of said band and having extensible parts foldable into underlying relation to said band so as to be concealed between the band and the hat to which said band is applied.

2. The combination with a discontinuous band having fastening means to unite its ends in meeting relation to detachably mount the same upon a hat, of a hat cover member secured to the inner face of said band and having extensible parts foldable into underlying relation to said band so as to be concealed between the band and the hat to which said band is applied.

3. In combination, a discontinuous hat band having fastening means to unite its ends in meeting relation, and a foldable hat cover; said hat cover comprising a main body secured to the inner side of said band, said main body having a free marginal portion foldable relative to one longitudinal edge of said band, a skirt portion foldable relative to the other longitudinal edge of said band, and a foldable top sheet connected with said marginal portion; said marginal portion, top sheet and skirt portion being foldable to underlie said band so as to be concealed between the band and a hat to which said band is applied; cooperative fastener means for uniting said top sheet and marginal portion, when unfolded, to form a protective covering to envelop the crown of a hat; and means to retain said skirt portion, when unfolded, in covering relation to the brim of said hat.

4. In combination, a discontinuous hat band having fastening means to unite its ends in meeting relation, and a foldable hat cover; said hat

cover comprising a main body secured to the inner side of said band, said main body having a pleated free marginal portion foldable relative to one longitudinal edge of said band, a pleated skirt portion foldable relative to the other longitudinal edge of said band, and a foldable top sheet connected with said marginal portion; said marginal portion, top sheet and skirt portion being longitudinally foldable relative to said band so as to underlie the same for concealment between the band and a hat to which the band is applied; cooperative fastener means for uniting said top sheet and marginal portion, when unfolded, to form a protective covering to envelop the crown of a hat; the pleats of said skirt portion adjacent to its free longitudinal edge having perforations therethrough, an elastic member threaded through said perforations, said elastic member having its end portions secured to said skirt portion, and cooperative fastener elements at the meeting ends of said skirt portion, whereby, when said skirt portion is unfolded to extend over the brim of said hat with its free longitudinal edge portions inturned around the margin of said brim and secured by said last named fastener elements, said elastic member is tensionally stretched to contract and retain said skirt member against displacement from said brim.

5. In combination, a discontinuous hat band having fastening means to unite its ends in meeting relation, and a foldable hat cover; said hat cover comprising a main body secured to the inner side of said band, said main body having a pleated free marginal portion foldable relative to one longitudinal edge of said band, a pleated skirt portion foldable relative to the other longi-
